[57] CLAIM

The ornamental design for a plane for wood carving, substantially as shown.

DESCRIPTION

FIG. 1 is a side elevational view of a plane for wood carving showing my new design;

FIG. 2 is a front elevational view thereof;

FIG. 3 is a rear elevational view thereof;

FIG. 4 is a side elevational view thereof, opposite to FIG. 1;

FIG. 5 is a bottom plan view thereof; and

FIG. 6 is a top plan view thereof.

FIG. 1

FIG. 2

FIG. 3

FIG. 4

FIG. 5

FIG. 6

UNITED STATES PATENT OFFICE
CERTIFICATE OF CORRECTION

Patent No. D-247,545 Dated March 21, 1978

Inventor(s) Jonathan Bonner

It is certified that error appears in the above-identified patent and that said Letters Patent are hereby corrected as shown below:

Please correct the spelling of the inventor's name as follows:

Jonathan [Banner] Bonner

Signed and Sealed this

Fourteenth Day of November 1978
